UNITED STATES PATENT OFFICE

93,251

DESIGN FOR A RANGE

Arthur Stockstrom and Almer H. Brodbeck, St. Louis, Mo., assignors to American Stove Company, St. Louis, Mo., a corporation of New Jersey

Application May 31, 1934, Serial No. 51,984

Term of patent 14 years

To all whom it may concern:

Be it known that we, ARTHUR STOCKSTROM and ALMER H. BRODBECK, citizens of the United States, residing at St. Louis, and State of Missouri, have invented a new, original, and ornamental Design for Ranges, of which the following is a specification, reference being had therein to the accompanying drawing.

The accompanying drawing is a perspective view of a range, showing our design.

The predominating features of our new design for ranges comprise a centrally arranged roasting and broiling compartment provided with a single door for both compartments, the top of the roasting compartment being closed, and two

short burner compartments each located at opposite sides of said central compartment with their upper ends in substantially a horizontal plane with the upper end of the said central portion, an open depending supporting framework for said compartments, and a vertically arranged panel located at the rear edges of the said compartments.

We claim:

The ornamental design for a range as shown and described.

In testimony whereof, we hereto affix our signatures.

ARTHUR STOCKSTROM.
ALMER H. BRODBECK.
